CLAIM

The ornamental design for a hand guard for firearms, as shown and described.

DESCRIPTION

FIG. 1 is a front perspective view of the hand guard for firearms,

FIG. 2 is a front elevation view of FIG. 1, the rear view being a mirror image;

FIG. 3 is a right side elevational view of FIG. 1, the left side being a mirror image;

FIG. 4 is a top plan view of FIG. 1; and,

FIG. 5 is a bottom plan view of FIG. 1.

The broken lines in the figures are shown to illustrate unclaimed portions of the invention and form no part of the claimed design.
